Primary Examiner — Joseph Kukella*Assistant Examiner* — Heather Ann Laaveg Wencl(74) *Attorney, Agent, or Firm* — Carmel Patent Agency;
Robert Ballarini(57) **CLAIM**

The ornamental design for an indicator light, as shown and described.

DESCRIPTION

FIG. 1 is a front perspective view of the indicator light according to our design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof.

The portions shown in broken line are for illustrative purposes only and form no part of the claimed design. The portion in long dash, short dash broken line depicts a boundary that forms no part of the claimed design.

1 Claim, 5 Drawing Sheets(56)
